UNITED STATES PATENT OFFICE.

JAMES E. VAN NESS, OF CHICAGO, ILLINOIS.

VAPORIZER.

No. 830,626.

Specification of Letters Patent.

Patented Sept. 11, 1906.

Application filed February 23, 1905. Serial No. 246,960.

To all whom it may concern:

Be it known that I, JAMES E. VAN NESS, a citizen of the United States, residing at Chicago, in the county of Cook and State of Illinois, have invented certain new and useful Improvements in Vaporizers, of which the following is a specification.

This invention relates to vaporizing and nebulizing devices of that class which are used in the administration of medicine in the form of a medicated vapor or nebulus to diseased organs, more especially those of the nose, throat, and lungs; and the invention has for its leading object to provide an improved device of this class whereby a much stronger gas or vapor can be generated than has heretofore been possible and whereby also the essential oils of the medicine employed can be taken up and carried over in such strength and highly-divided form as to be of practical value and efficiency through local application in contradistinction to many vaporizers and inhalers now in use which deliver merely a current of air or weak vapor impregnated with little more than the odors of the medicinal agents used therein.

The device of this invention, in common with many similar devices now in use, employs an outer vessel containing a pungent solution, such as ammonia, and an inner vessel containing an acid solution, such as hydrochloric acid, with means for forcing a current of air into said inner vessel, then conducting the acid fumes therefrom over into the outer vessel in contact with the ammonia solution therein, and thence conducting the resultant ammonium-chlorid gas through a suitable discharge tube or nozzle to the affected organs of the patient; but the present invention is distinguished from prior devices of this class in several important respects, as follows: First, in the employment of a special construction of the air and vapor conducting tubes of the device, whereby the air introduced to the acid solution is caused to carry over more acid fumes and of greater strength than have heretofore been possible of attainment, thus permitting the use of a stronger ammonia solution, and whereby the acid fumes are caused to act similarly upon the ammonia solution in the generation of a strong ammonium-chlorid gas or vapor; second, in the employment of a flexible discharge tube having a medicated sponge located in

an interchangeable delivery-nozzle directly 55 in the path of the pure gas or vapor emitted by the device, whereby said gas or vapor takes up and carries over the essential oils containing the principle of the medicine employed without requiring the globule or globules to travel through said discharge-tube, to which it is likely to adhere; third, in the employment of a glass or jar surrounding the gas-generating devices and containing a water-bath in which the gas or vapor generated 65 in the vaporizer is thoroughly washed and relieved of any impurities or excess of either agent prior to its discharge and subsequent medication, this feature being especially designed for the apparatus as used by physicians, in which case the entire apparatus may be conveniently packed in a portable case; fourth, in the employment of vapor-conducting tubes and other parts of hard rubber as distinguished from the glass tubes heretofore 75 used in such devices.

The invention also includes as an important feature contributing to its simplicity of construction a cored closure or stopper which affords a passage for the acidified gas directly 80 to the tube leading to the ammonia solution and also a passage for the gas generated from the interior of the containing vessel to the discharge-tube.

My invention in its preferred form is illustrated in the accompanying drawings, where-

Figure 1 is a vertical sectional view with the air-inlet and gas-discharge tubes shown partly in elevation, and Fig. 2 is a bottom 90 plan view of the acid-gas-conducting tube of the device.

Referring to the drawings, 5 designates an outer vessel, preferably in the form of a glass jar, having an externally-threaded top portion 5^a, to which is adapted to be screwed a cap 6, preferably of hard rubber. The upper end of the jar 5 is occupied by a stopper-plate 7, consisting, preferably, of a hard-rubber circular disk of considerable thickness which is provided at its upper end with a horizontally-extending flange 7^a, resting upon the upper end of the jar through an interposed packing ring or gasket 8 and a depending externally-threaded flange 7^b. The cap 6 has an internal annular shoulder 6^a formed thereon, which when the cap is screwed onto the jar securely clamps the

stopper 7 to its seat on the upper end of said jar.

Secured to the depending flange 7^b is an inner vessel 9, into which extends a pair of tubes 10 and 11, both of which are screwed at their upper ends into internally-threaded recesses or sockets 12 and 13 in the lower face of the stopper-plate 7. The upper ends of tubes 10 and 11 are in free communication with each other by means of a horizontal duct 14, formed in and through the stopper-plate 7 between the recesses 12 and 13. Secured in the stopper-plate 7 and extending from the upper face thereof a considerable distance into the tube 10 is a smaller tube 15, which is provided with a minute axial bore 15^a, substantially capillary in size. The lower end of tube 10 is closed, while the lower end of tube 11 is provided with one or a series of minute apertures or perforations 11^a, Fig. 2. Secured in the bottom of the vessel 9, preferably centrally thereof, is an upstanding gas-discharge tube 16, open at both ends and extending to something less than the full height of the vessel 9. Secured to the upper face of the stopper-plate 7, centrally thereof, is a short tube 17, having a reduced externally-threaded upper portion 17^a passed through the cap 6 by an air-tight joint, to which is attached, by means of a nipple 18, a flexible discharge tube or hose 19. Cored in the stopper-plate 7 is a rectangular duct 20, the short vertical portion of which registers with the bore of the tube 17 at its lower end, while the horizontal portion leads to and through the annular marginal surface of the stopper-plate, communicating freely at that point with the interior of the outer jar 5. To the remote end of the hose 19 may be connected through a suitable axially-bored connection piece or stem 21 a nipple 22, having its bore somewhat enlarged to provide a chamber 22^a, adapted to contain a medicated sponge 23.

Tapping the cap 6 is a nipple 24, to which is attached a hose 25, through which compressed air may be supplied from a hand bulb, pump, or any other suitable or convenient source of compressed air.

The outer vessel 5 is designed to be partially filled with water. The tube 10 is filled to a level slightly below the lower end of the inner tube 15 with a suitable acid, such as hydrochloric acid, and the vessel 9 is filled, preferably to a level slightly above the lower end of the tube 11, with a neutralizing agent, such as strong ammonia-water. The sponge 23 is loaded with the essential oil of any suitable medicinal drug, so as to impart to the gas forced therethrough an agreeable aroma or medicinal quality, or both, as may be desired.

In the operation of the device compressed

air introduced through the tube 25 and nipple 24 fills the chamber between the cap 6 and stopper 7, from which such compressed air flows in an attenuated stream, but with considerable speed and force, through the capillary bore of the tube 15, issuing from the lower end of the latter in a fine jet, which impinges upon and penetrates the upper portion of the acid contained in tube 10, producing a bubbling and boiling of such acid and generating acid fumes or gas in greater volume and of greater strength than where the air-current merely passes over the surface of the acid. These rise through the tube and flowing through the communicating duct 14 enter and fill the tube 11 and by their pressure expel the ammonia-water in the latter tube through its lower end and issuing in fine jets or sprays through the series of apertures 11^a thoroughly mix with the ammonia-water, rising therefrom into the upper part of the vessel 9 in the form of a strong ammonium-chlorid gas, which gas flowing downwardly through the tube 16, is thoroughly washed and cleansed of all impurities in the water surrounding the lower end of the vessel 9, being relieved therein also of an excess of either acid or ammonia and rising therefrom in a smooth and perfectly-neutralized condition. The purified gas, filling the outer vessel 5 above the water, finds its way through the duct 20 of the stopper-plate to the discharge-tube 17 and thence through the connection 18, tube 19, connection 21, and medicated sponge 23 in the nipple 22 to the point of application.

The capillary bore of the air-conducting tube 15 is so fine as to produce a strong air-jet of an almost needle-like character well adapted to pierce the underlying body of acid liquid and effect the generation of acid fumes of great strength. Similarly the finely-divided and jet-like condition in which the said fumes are sprayed into the ammonia-water effects a perfect combustion and neutralization of the acid by the ammonia, for which purpose a very strong solution of ammonia, on account of the strength of the acid fumes, must be used. The increased strength of chemicals employed thus gives an increased strength of resultant ammonium chlorid. The location of the entire vaporizing apparatus within the inclosing vessel or jar containing a washing and cleansing liquid makes a simple and compact device wherein the cleansing fluid is capable of being renewed by simply unscrewing the cap 6 and lifting out the stopper-plate and its attached parts. In some cases it is desirable to administer the gas in a warm state, and this may easily be effected in the present apparatus by supplying hot water as the gas-cleansing liquid. The provision of a considerable

space between the cap 6 and the stopper-
plate 7 affords an air-reservoir at such point,
which is of considerable importance as con-
tributing to the uniformity and steadiness of
5 the flow of compressed air into and of gas
from the device.

The several vapor-conducting tubes of the
apparatus and, in fact, all the parts thereof
10 except the outer jar 5 and the inlet and dis-
charge tubes 25 and 19 are by preference
made of hard rubber, the benefits and advan-
tages of this material residing in the elimina-
tion of the expense and waste incurred where
15 such parts are made of glass, as is the com-
mon practice at present, and in the facility of
coring the several parts, the sizes of the ports
and passage-ways therein being capable of
greater accuracy and uniformity in their
20 manufacture in a molded material like rub-
ber than in a drawn material such as glass.

I claim—

1. In a vaporizer of the type described, the
combination with a vessel adapted to contain
ammonia and provided with a gas-discharge
25 tube opening through its base, of a closure
for said vessel having an acid-containing tube
depending therefrom and an acid-gas-con-
ducting tube also depending therefrom, said
latter tube communicating at its upper end
30 with said acid-containing tube through a pas-
sage cored in said closure and having its lower
end provided with one or more contracted
discharge-apertures, an air-inlet tube leading
into said acid-containing tube, and means
35 for discharging the ammonium-chlorid gas
communicating with said discharge-tube of
the ammonia vessel, substantially as de-
scribed.

2. In a vaporizer of the type described, the
40 combination with a vessel adapted to contain
ammonia and provided with a gas-discharge
tube opening through its base, of a closure
for said vessel, a cap surmounting said clo-
sure and providing between the latter and
45 itself an air-reservoir, an air-inlet tube com-
municating through said cap with said reser-
voir, an acid-containing tube depending from
said closure, an acid-gas-conducting tube also
depending from said closure, the latter tube
50 communicating at its upper end with said
acid-containing tube through a passage cored
in said closure and having its lower end pro-
vided with one or more contracted discharge-
apertures, an air - inlet tube having a con-
55 tracted air-passage communicating at its up-
per end with said air-reservoir and dipping
into said acid-containing tube, and means for
discharging the ammonium-chlorid gas com-
municating with said discharge-tube of the
60 ammonia vessel, substantially as described.

3. In a vaporizer of the type described, the
combination with an outer vessel adapted to
contain a gas-washing liquid, of a cored plate

covering the upper end thereof, a vessel de-
pending from said plate adapted to contain 65
an ammonia solution, a tube secured in the
base of said ammonia vessel extending in-
wardly thereof and open at both ends, an
acid-containing tube depending from said
70 plate within said ammonia vessel, an air-inlet
pipe leading to the interior of said acid-con-
taining tube, an acid-gas-conducting tube de-
pending from said plate into said ammonia
vessel communicating at its upper end with
75 said acid-containing tube by a cored passage in
said plate and at its lower end delivering into
said ammonia vessel through one or more con-
tracted apertures, and a gas-delivery tube
communicating through a duct in said plate
80 with the interior of said outer vessel, substan-
tially as described.

4. In a vaporizer of the type described, the
combination with an outer vessel adapted to
contain a gas-washing liquid, of a cored plate
covering the upper end thereof, a hollow cap 85
secured to the upper end of said outer vessel
serving to clamp said cored plate thereto and
providing between itself and the latter an air-
reservoir, an ammonia vessel depending from
said cored plate within said outer receptacle,
90 a discharge-tube opening through the base of
said ammonia vessel, an acid-containing tube
depending from said cored plate within said
ammonia vessel, an air-inlet tube having a
contracted air-passage secured in said cored 95
plate communicating at its upper end with
said air-reservoir and at its lower end with
the interior of said acid-containing tube di-
rectly over the surface of the acid therein, an
acid - gas - conducting tube depending from
100 said plate into said ammonia vessel communi-
cating at its upper end with said acid-contain-
ing tube by a cored passage in said plate and at
its lower end delivering into said ammonia
vessel through one or more contracted aper-
105 tures, an air-supply tube tapping said cap, and
a gas-delivery tube passed through said cap
and air-reservoir and communicating with the
interior of said outer vessel through a suitable
duct in said cored plate, substantially as de-
110 scribed.

5. In a vaporizer of the type described, the
combination with a vessel adapted to contain
an ammonia solution, and a cover therefor,
of an acid-containing tube depending from 115
said cover, an air-conducting tube also de-
pending from said cover and entering said
acid-containing tube, and a conducting-tube
for the acid fumes also depending from said
cover, said air and acid conducting tubes be-
ing made of hard rubber and provided with
120 minute perforations for the discharge there-
through of air and acid gas in minute streams
directly into the adjacent liquids, substan-
tially as and for the purposes described.

6. In a vaporizer of the type described, the

combination of an outer vessel adapted to contain a gas-washing liquid, of a plate covering the upper end thereof, a vessel depending from said plate adapted to contain an ammonia solution, an acid-containing tube depending from said plate within said ammonia vessel, an air-inlet pipe leading to the interior of said acid-containing tube, an acid-gas-conducting tube provided with minute perfora-

tions establishing communication between the acid-containing tube and the ammonia vessel, and means to conduct the gas through the washing liquid.
